UNITED STATES PATENT OFFICE.

ROBERT T. CLYDE, OF MARION CENTER, PENNSYLVANIA.

LOCK FOR END GATES.

Application filed January 29, 1924. Serial No. 689,295.

To all whom it may concern:

Be it known that I, ROBERT T. CLYDE, a citizen of the United States, residing at Marion Center, in the county of Indiana, State of Pennsylvania, have invented certain new and useful Improvements in Locks for End Gates; and I do hereby declare the following to be a full, clear, and exact description of the invention, such as will enable others skilled in the art to which it appertains to make and use the same.

This invention relates to new and useful improvements in locks for the end gates of dump wagons and the like.

15 The primary object of the present invention is to provide a device of this character which is so constructed and arranged that the locking and unlocking of the end gate may be accomplished from the seat of the 20 driver of the vehicle.

Another object of the present invention is to provide a device of this kind which will be thoroughly efficient and practical in its 25 operation and which, when in locked position, will withstand the vibration caused by the movement of the vehicle, so that all danger of the end gate becoming accidentally unlocked will be obviated.

A still further object of the present invention is to provide a device of this nature which is of exceedingly simple construction and wherein a minimum number 30 of elements are employed.

With these and other objects in view, the 35 invention resides in the novel construction and arrangement of parts as will be more fully described hereinafter, illustrated in the accompanying drawing and particularly pointed out in the appended claim.

40 In the drawings:

Figure 1 is a side elevation of a device constructed in accordance with the present invention, as applied to a dump wagon, parts of the wagon being shown in section.

45 Figure 2 is a bottom plan view of the same.

Figures 3 and 4 are front and rear views, respectively of the invention applied to a vehicle, the dotted lines showing the position 50 of the elements when the gate is unlocked while the full lines show the position of the elements when the gate is locked.

Referring more particularly to the accompanying drawings, in which are illustrated 55 one form which may be used for carrying the invention into practice, it will be noted

that there is disclosed a dump wagon or the like embodying the side members 10, the bottom 11, the front end 12 and the end gate 13, which is suitably mounted for swinging movement. The bottom 11 of the wagon projects slightly beyond the front end 12 and is provided with a groove 14, which extends longitudinally thereof from one end to the other. It is in connection with 60 a wagon of this type that the present invention is employed.

Generally speaking, the invention comprises the two elements 15 and 16, the former of which is arranged for holding the 70 gate in closed position, while the latter is employed to lock the end gate holding means in its proper position.

The element 15 comprises a bar or rod 75 17, which is positioned within the longitudinally extending groove 14 and is held therein by suitable fastening means. The rear end portion of this bar 17 is bent at right angles to form the latch 18, which is arranged to engage the outer face of the 80 lower free end of the end gate, whereby to hold it in closed position. The front end portion of the bar 17 is also bent angularly as indicated at 19, and this portion 19 is bent in the same direction as the latch member 18, so that they are substantially parallel with each other. The front end portion is again bent, however, and this time to the left, to form the lever 20, and the terminal portion of this lever is bent rearwardly to 85 provide a stop 21, the object of which will be noted hereinafter.

The element 16, as already stated, is employed to lock the end gate holding means in the desired position, and this element comprises essentially the short, substantially vertical pin 22, which passes through the projecting portion of the bottom of the wagon and is movably held therein, by suitable means. The upper end portion of this pin 95 100 is bent at substantially right-angles to the vertical portion thereof, in order to provide the catch 23.

Both of the elements are arranged for rotary, oscillating movement with the result 105 that, in the operation of the device, when it is desired to unlock the end gate, it is necessary to cause the elements to resume the positions shown in the dotted lines. This is accomplished by first turning the catch 23 110 to the right after which the lever can be swung also to the right and when this has

been done, the latch member 18 assumes a substantially horizontal position with the result that the gate is free to swing open. When the body of the wagon is lowered, the 5 gate will automatically swing to closed position through the action of gravity. The lever 20 can then be swung to the left and the catch also turned in the same direction until it engages the upper face of the lever. 10 The stop 21 abuts against the bottom of the wagon when the lever is swung to the right and thus prevents the said lever from swinging downwardly below the wagon. The stop 21 further prevents the swinging of the lever 15 20, should the catch 23 be accidentally caused to swing entirely to the left.

From the above, it will be seen that there has been provided a simple, yet practical device which is capable of attaining all of the 20 objects and performing all of the functions claimed and it is to be understood that such changes in the construction and arrangement of the device may be made, as properly fall within the scope of the appended claim.

25 It is also to be noted that the groove in the

bottom of the wagon is not essential to the successful operation of the device, inasmuch as the bar or rod 17 may be supported by means of suitable brackets which would provide bearings therefor.

30

What I claim as new and useful and desire to secure by Letters Patent is:

The combination with a wagon box and the depending pivoted end gate thereof, of a rock shaft mounted centrally and longitudinally on the bottom of the box, the rear end of the shaft being extended at right angles for engagement with the lower free end of the end gate to hold the same in closed position, the other end of the shaft being extended in parallel relation to the first-named end and thence laterally at right angles thereto, the terminus of said end being extended inwardly in parallel relation to the shaft, and a horizontally swingable detent 40 carried by the bottom of the wagon box, beyond one end thereof, for retaining engagement with the last-named end of the shaft.

35

45 In testimony whereof, I affix my signature.

ROBERT T. CLYDE.
